SAFETY MITTEN

William E. Probert, Spokane, Wash.

Application February 17, 1950, Serial No. 144,691

3 Claims. (Cl. 2—158)

1

This invention relates to a workman's mitten, and particularly to a safety mitten including a crush-resistant shield for protecting the ends of the fingers.

Leather mittens are commonly worn in the manual handling of heavy materials such as steel plate, brick and stone. While these protect the hands from cuts and abrasions they afford little protection to the fingers if caught between successive plates in a pile or between the stones or bricks being handled. Statistical studies of accident records show that finger injuries account for approximately 35% of all bodily injuries and are particularly prevalent in the masonry trades.

Accordingly it is an object of the present invention to provide a mitten having in the finger-receiving portion thereof a shield of crush-resistant material which encompasses the backs of the fingers.

Other objects will become apparent from the following specification when read in conjunction with the attached drawings wherein:

Figure 1 is a back view of the mitten of the present invention with the protective shield in place;

Figure 2 is a section through the finger-receiving portion of the mitten taken along line II—II of Figure 1;

Figure 3 is a transverse section taken along the line III—III of Figure 1; and

Figure 4 is a perspective of the crush-resistant shield.

With particular reference to the drawings the numeral 2 indicates a piece of leather or other flexible, protective material forming the back of the mitten and the numeral 4 indicates a similar piece of leather of appropriate shape forming the palm or front-piece. The pieces 2 and 4 are joined together to provide the finger-receiving portion 5. The thumb-receiving portion is formed of additional pieces and is indicated in general by the reference numeral 6. A strap 8 is provided at wrist level to retain the mitten on the hand.

Attached to the back of the finger-receiving portion 5, along the bottom peripheral edges thereof is an additional patch of material 10 of the same general shape as the back piece 2 but slightly wider and shorter than the latter. The patch 10 is secured to the back of the mitten by means of staples 12 and rivets 14, which also serve to join the front and back pieces, thus providing a pocket 15 between piece 2 and patch 10 which pocket accommodates a half-cup shaped shield 16. The latter is disposed in the pocket 15 with its open end 17 toward the top of the pocket and its concave side toward the back-piece 2. The shield is formed of a single piece of steel or other crush-resistant material such as reinforced plastic. The shield extends substantially the width of the mitten, is of such depth as to cover the fingers from the tips thereof to at least the sec-

2

ond joint and has sufficient crown or height to permit free movement of the fingers in the finger receiving portion of the mitten. The lip portions 18 of the half-cup are preferably flattened or flanged as indicated in Figure 4 so as to avoid cutting the back-piece 2. The shield 16 is maintained in position by the snap-fasteners 20 and can readily be removed by disengaging these fasteners.

In the above described embodiment of my invention, the shield is maintained out of direct contact with the fingers by the back-piece 2. This is advantageous in cold weather. However, if desired, the shield could be fitted in the bottom of the finger-receiving portion of the mitten or be directly attached to the palm and back pieces forming an integral part of the latter. Either of these alternate arrangements also combines a flexible covering for the front of the hand with a rigid back portion which encompasses the backs of the fingers.

While I have shown and described a preferred embodiment of my invention, it is apparent that other modifications can be made without departing from the scope of the appended claims.

I claim:

1. In a workman's mitten having a finger-receiving portion, a patch of suitable material attached to the back of said finger-receiving portion along the bottom peripheral edges thereof to form a pocket, a half-cup shaped shield of rigid crush-resistant material disposed in said pocket with the concave side of said shield opposite the back of said finger-receiving portion and the open end of said shield toward the top of said pocket, and means for detachably holding said shield in position in said pocket.

2. In a workman's mitten having a finger-receiving portion, a patch of suitable material attached to the back of said finger-receiving portion along the bottom peripheral edges thereof to form a pocket, a shield of rigid crush-resistant material disposed in said pocket and means for holding said shield in position in said pocket.

3. In a workman's mitten having a finger-receiving portion, a half-cup shaped shield of rigid crush-resistant material removably attached to the finger receiving portion to move therewith and positioned to encompass the ends and backs of the fingers of a hand in said finger-receiving portion.

WILLIAM E. PROBERT.
